UNITED STATES PATENT OFFICE.

DAVID TOMLINSON BAIRD WOOD, OF LONDON, ENGLAND.

APPARATUS FOR FILING CARDS.

1,419,656.

Specification of Letters Patent. Patented June 13, 1922.

Application filed January 26, 1921. Serial No. 440,016.

To all whom it may concern:

Be it known that I, DAVID TOMLINSON BAIRD WOOD, a subject of the King of Great Britain, residing at British Museum, London, England, have invented new and useful Improvements in Apparatus for Filing Cards, of which the following is a specification.

This invention relates to apparatus for 10 filing cards and more particularly to wheel files.

According to one feature of this invention to one end of a card container is hinged a wedge or flap which is automatically moved 15 outwards when the container is moving towards one of its vertical positions and remains in this position until the container is moved towards the other vertical position.

The wedge may be triangular and such 20 that the side which comes against the cards in its outward position is parallel with the opposite end of the container.

The cards according to another feature of 25 this invention are secured in position by wires one of which may be a fixture, whilst means are provided for sliding the other wire towards the fixed wire.

Or the cards may be prevented from falling 30 out of a container by narrow bands covering their edges.

In a modification of the card carrier, the innermost edges of the fixed and sliding floors may be formed into a rim, which in turn has formed on it a flange.

35 The invention is illustrated in the accompanying drawings in which Figure 1 is a section on the line A—A, Figure 2, of a container forming part of a wheel; Figure 2 is a plan; Figure 3 is a section on the line B—B Figure 1; and Figure 4 is a perspective view. Figures 5 and 6 show the arrangement of a complete wheel. Figures 7, 8, 9 and 10 show views of modifications, Figure 7 being a section on the line C—C 45 Figure 8, and Figure 8 a plan of a container. Figure 9 shows an alternative construction to a larger scale of the card carrier, and Figures 10 shows to a smaller scale an arrangement in which the whole floor of 50 the container is movable.

Referring to Figures 1 to 6, the sides 1 of the wheel form the sides of the containers, and the ends 2 of the containers form the partitions in the wheel.

55 One side of each partition 2 is formed by a supplemental member 2' and has hinged

to it a triangular flap 3 in such a manner that the flap can lie in one extreme position parallel with the partition 2 and in the other extreme position at right angles thereto in 60 which latter position the lower edge 4 is parallel with the partition forming the opposite end of the container.

5 is the fixed floor of the container extending half way across and 6 is a movable floor 65 extending somewhat less than half way across and adapted to slide in grooves formed in the partition 2, and a transverse strip 7 projecting at one end beyond a side of the container may be conveniently made 70 fast with the floor 6, for the purpose of sliding the floor 6 when it is desired to remove the cards.

8 and 9 are wires parallel with the sides 1 of the container and arranged somewhat 75 above the floors 5 and 6; the turned-out ends of the wire 8 are inserted in holes in the partition member 2' while the turned-down ends of the wire 9 are inserted in holes in the floor 6, and 10 are V-shaped springs 80 carried by the partitions and arranged to normally move the sliding floor away from the fixed one 2, and adapted to return the sliding floor 6 to its original position when released. 85

The flaps 3 are preferably weighted with a heavy material such as a block of lead 11, so that when approaching a vertical position, the flaps move outward and keep the cards from assuming an inconvenient position which could occur unless the container was inconveniently filled to prevent any movement of the cards. Moreover it is found in practice that even if the cards are not caught by the wires 8 and 9, there is 95 little tendency for them to fall out of the container when the wheel is rotated, this being due to the outward movement of the flaps 3.

Referring now to Figures 7 and 8, similar 100 parts having similar numerals, instead of retaining the cards by means of wires, they may be free in the container and prevented from falling out when in the inverted position by means of bands or straps 12 carried 105 by the upper edges of the sides 1 of the wheel and projecting inwardly over the upper corners of the cards. There is a clearance between a side 1 and one of the bands 12 to allow for the insertion or withdrawal 110 of the cards. These bands may be movable, but as illustrated they are fixed. By using

this construction the number of cards which can be placed in the container is limited.

Referring to Figure 9, instead of having wires fixed to the floors, the floors 5 and 6 may be made of metal and have their innermost faces formed into a rim 13, the upper edge of which is formed into a return-bent flange 14. This figure shows a card 15 in position.

10 In the modification shown in Figure 10, the floor is made in one piece and slides as a whole. It is normally retained by the friction of the engaging parts. In this modification the V-shaped springs 10 are 15 omitted.

What I claim is:—

1. In apparatus for filing cards, the combination of a container, a card-retaining element carried thereby, a sliding floor, and 20 a second card-retaining element carried by said floor and cooperating with said first element.

2. In apparatus for filing cards, the combination of a card-retaining wire, a sliding floor, and a second card-retaining wire carried by said floor and movable towards and away from said first wire.

3. In apparatus for filing cards, the combination of a card-retaining element, a sliding floor, a second card-retaining element carried by said floor and movable towards and away from the first element, and springs located adjacent the ends of said elements and holding said elements against 35 accidental movement from card-retaining position.

4. In apparatus for filing cards, the combination of a card-retaining wire, a sliding floor, a second card-retaining wire carried 40 by said floor and movable towards and away from the first wire, and springs located adjacent the ends of said wires and holding said wires against accidental movement from card-retaining position.

45 5. In apparatus for filing cards, the combination of a card-retaining wire, a sliding floor, a second card-retaining wire carried by said floor and movable towards and away from the first wire, and V-shaped springs 50 located adjacent the ends of said wires and holding said wires against accidental movement from card retaining position.

55 6. In aparatus for filing cards, the combination of a casing, a card-retaining wire carried thereby, a sliding floor, and a second card-retaining wire carried by the floor and movable therewith toward and away from the other wire.

7. In apparatus for filing cards, the combination of a casing, a card-retaining wire

carried thereby, a sliding floor, a second card-retaining wire carried by the floor and movable therewith towards and away from the other wire, and springs for preventing accidental sliding movements of said floor 65 to release the cards.

8. In apparatus for filing cards, the combination with a card-container having ends, of a triangular flap hinged to one end of the container and adapted to occupy two 70 positions, in one of which it lies parallel to said end, and in the other, at right angles thereto.

9. In apparatus for filing cards, the combination with a card-container having ends 75 inclined relatively to each other, of a triangular flap hinged to one end of the container and adapted to occupy two positions, in one of which it lies parallel to said end, and in the other, at right angles thereto, the 80 edge facing the cards when the flap is in the latter position being parallel to the other end of the container.

10. In a rotary file, the combination of rings forming the sides of a plurality of 85 containers, radial partitions forming their ends, and a triangular flap pivoted to one side of each partition, said flap adapted to swing to a position at right angles to the partition, and when in said position having 90 its outward edge parallel to the opposite end of the container.

11. In a file, the combination with a plurality of containers arranged in a circle, of 95 card - retaining elements carried thereby, floors adapted to slide relatively to the card-retaining elements, and other card-retaining elements fixed one to each sliding floor.

12. In a file, the combination with a plurality of containers arranged in a circle, of 100 card - retaining elements carried thereby, floors adapted to slide relatively to the card-retaining elements, other card-retaining elements fixed one to each sliding floor, and a projecting strip fixed to each sliding floor 105 whereby it may be moved.

13. In a rotary file, the combination with a plurality of containers arranged in a circle, of card-retaining elements carried thereby, floors adapted to slide relatively 110 to the card-retaining elements, other card-retaining elements fixed one to each sliding floor, a projecting strip fixed to each sliding floor whereby it may be moved, and springs adapted to prevent accidental sliding of the floors.

In testimony that I claim the foregoing as my invention I have signed my name this 5th day of January, 1921.

DAVID TOMLINSON BAIRD WOOD.
